A. R. ST. CLAIR

ILLUMINATING DEVICE FOR SIMULATING DAYLIGHT

Filed June 20, 1925

INVENTOR:

Arthur Reginald St. Clair.

BY ARTHUR R. ST. CLAIR

ATTORNEY

UNITED STATES PATENT OFFICE.

ARTHUR REGINALD ST. CLAIR, OF WHITLEY BAY, ENGLAND.

ILLUMINATING DEVICE FOR SIMULATING DAYLIGHT.

Application filed June 20, 1925. Serial No. 38,537.

To all whom it may concern:

Be it known that I, ARTHUR REGINALD ST. CLAIR, a subject of the King of Great Britain and Ireland, residing at "Arncliffe," 5 Waterford Crescent, Whitley Bay, in the county of Northumberland, England, have invented certain new and useful Improvements in Illuminating Devices for Simulating Daylight, and for which I have filed application in Great Britain, Nov. 30, 1923, of 10 which the following is a specification.

This invention relates to illuminating devices, and has for its object to provide a device which may be applied to existing metal 15 filament electric lamps, arc lamps or incandescent gas lamps—hereinafter referred to generally as "lamps"—so as to produce a light which will allow of the accurate comparison of colours, will lessen the glare effect of such lamps, and will generally be of 20 similar quality to daylight.

This object is attained according to the present invention by providing a light filter through which the rays of the lamp are 25 caused to pass, said filter comprising a translucent medium such as glass, mica, or the like, having a tint known in the coloured glass trade as "Cobalt blue."

As the tints of glass vary with the different makers, the limits of shades between 30 which the desired results will be attained, are best defined according to the analyses given by Lovibond's tintometer. According to the readings of this instrument, the tint 35 may vary between blues of the following analyses:—Blue 3.5, red 0.05, and blue 6.0, red 0.50.

For matching colours the best results are obtained by providing a white frosted glass 40 next to the filter medium the tint of which is preferably:—Blue 4.10 and red 0.20, according to the above standard. Alternatively, the filter medium itself may be frosted, and in the case of a glass filter the most 45 suitable frosting is that obtained by the treatment known as "acidating," this treatment giving a finer "frost" than that obtained by the sand-blast treatment. Again, in the case of an electric light bulb, the bulb 50 itself may be frosted, preferably by acidating, and the filter medium left plain.

In one form of the device according to the present invention, the filter comprises a 55 plate of glass of cobalt blue tint according to the above formula, and a plate of white

frosted glass, both plates being of about the thickness of window glass. The said plates are held together, for example by means of lead strips bent over the edges of the two plates, and the resulting composite filter is 60 inserted in a detachable manner into the opening of an opaque shade adapted to fit over the lamp to which the device is to be applied, so that when the shade and filter are in position all the rays passing from the 65 lamp into the room have to pass through the filter.

The inside surface of the shade may be a reflector, preferably of a shape to cause all the reflected rays to pass through the filter— 70 parabolic, for example. The opening in the shade may be either at the side or at the bottom according to the particular use to which the device is to be put.

For incandescent gas lamps light-tight 75 ventilation apertures are provided at the upper and lower portions of the shade to allow of the circulation of air. Preferably, similar apertures are provided on the device for use with electric lamps in order to prevent the deposit of moisture on the glass. Further, additional apertures or perforations may be formed adjacent the edge of 80 the filter in order to prevent overheating of the latter.

The single figure of the accompanying 85 drawing is a sectional view of the bottom part of a lamp equipped with the invention.

Referring more particularly to the drawing, A' indicates the cylindrical portion of 90 the lamp casing having an internal flange A² formed at its lower end, on which flange there is a yielding packing C, the filter resting on said packing. The filter comprises a single tinted glass D divided into strips to 95 prevent cracking through overheating, and a plain frosted glass D¹ underneath, also in strips which are arranged at right angles to those of the tinted glass D. The two glasses are held together by a rim E of soft metal 100 such as lead or zinc.

I claim:—

1. A light filter for use with artificial light comprising a translucent medium having a tint lying between the following 105 analyses according to Lovibond's tintometer:—Blue 3.50, red 0.05, and blue 6.0, red 0.50.

2. A light filter for use with artificial light comprising a translucent medium hav- 110

ing a tint of the following analysis according to Lovibond's tintometer:—Blue 4.10, red 0.20.

3. A light filter for use with artificial light comprising a plurality of strips of translucent glass having a tint lying between the following analyses according to Lovibond's tintometer:—Blue 3.50, red 0.05, and blue 6.0, red 0.50, and a plurality of 10 strips of frosted glass placed against said strips of translucent glass, the strips of the one element being set at an angle to those of the other element.

4. A light filter for use with artificial light comprising a plurality of strips of translucent glass having a tint of the following analysis according to Lovibond's tintometer:—Blue 4.10, red 0.20, and a plurality of strips of frosted glass placed against said strips of translucent glass, the strips of the one element being set at an angle to those of the other element. 15

In witness whereof I have signed this specification.

ARTHUR REGINALD ST. CLAIR.
